ATTORNEY

UNITED STATES PATENT OFFICE.

WILLIAM J. BOHAN, OF ST. PAUL, MINNESOTA.

CAR-LADDER.

1,274,377.

Specification of Letters Patent.

Patented Aug. 6, 1918.

Original application filed July 12, 1915, Serial No. 39,288. Divided and this application filed April 7, 1917.
Serial No. 160,382.

To all whom it may concern:

Be it known that I, WILLIAM J. BOHAN, a citizen of the United States, residing at St. Paul, in the county of Ramsey and State of Minnesota, have invented a certain new and useful Improvement in Car-Ladders, of which the following is a full, clear, concise, and exact description, reference being had to the accompanying drawings forming a part of this specification.

This invention relates to improvements in car ladders.

The object of the invention is to provide an extremely rigid and efficient yet simple ladder construction more particularly adapted for all-steel freight cars and wherein the ladders and portions of the car frame mutually brace and strengthen each other. This application constitutes a division of my prior application No. 39,288, filed July 12, 1915, for improvement in freight cars.

In the drawing forming a part of this specification, Figure 1 is an end elevation of one end of a car showing my improvements in connection therewith. And Fig. 2 is a horizontal detail sectional view, taken on the line 2-2 of Fig. 1.

In said drawings, the end of the car is shown as having a single element A bent to form corner posts 10-10, end posts 11-11, diagonal bracing portions 12-12 and an upper cross connecting section 13 for the end posts 11. Said member A, as described in my said application No. 39,288, is preferably formed from a channel, the outermost flange thereof being flattened where the bends occur, as indicated at 14-14. The framework thus formed by the member A has riveted or otherwise rigidly secured thereto sheet metal sheathing 15 and dished top plate 16 to which the roof sheets 17 may be secured. As described in said application, the framework for the sides of the car is similarly formed by bending a channel into vertical posts and diagonal braces, and in Fig. 2 of the drawing, a section of the end post is indicated at 18. Where the two corner posts of a car end and car sides meet, the flange of one of said posts is bent to position parallel with the web of the channel, as indicated at 19 in Fig. 2 and said bent down flange is riveted to the ad-

jacent flange 20 of the other post. These riveted flanges 19 and 20 form a common stile for the side and end ladders, the side ladder comprising a series of rungs 21 and the end ladder a similar series of rungs 22. Said rungs 21 and 22 are secured to the stile at the corner and at their opposite ends to vertically extending stiles 23 and 24.

With the arrangement above described, it is apparent that the rungs of the two ladders brace and strengthen the corner posts of the car and the latter in turn provide a common stile of rigid construction for the ladders, thereby simplifying the construction and minimizing the number of parts required for the ladders.

I claim:

1. In car construction, a channel-shaped vertical post at one edge of the car end, a second vertical post at the end of the car side adjacent said first named post, the flanges of said two posts being riveted together, and side and end ladders, the rungs of said ladders at those ends located at the corner of the car being secured to said riveted flanges.

2. In car construction, the combination with a corner post formed by securing together projecting portions of the adjacent vertical posts of a car side and car end, of side and end ladders, said corner post forming a common stile projecting outwardly beyond the adjacent surface of the car for said ladders, the rungs of said ladders being secured to the said corner post and bracing it from both sides.

3. In a car ladder construction, the combination with a side ladder and an end ladder located at the corner of the car, each of said ladders comprising a series of rungs and a pair of stiles, the stile at the corner of the car being common to both ladders, said stile forming also the corner post of the car, all of said stiles being formed by commercial bars disposed on the outside of the car.

In witness that I claim the foregoing I have hereunto subscribed my name this 22nd day of March, 1917.

WM. J. BOHAN.
